(57) **CLAIM**

The ornamental design for an electrical connector, as shown and described.

DESCRIPTION

FIG. 1 is a left front perspective view of an electrical connector showing my new design. The right, front perspective view is a mirror image thereto;

FIG. 2 is a front elevation view thereof;

FIG. 3 is a rear elevation view thereof;

FIG. 4 is a top view thereof;

FIG. 5 is a bottom view thereof;

FIG. 6 is a left side elevation view thereof. The right side elevation view is a mirror image thereto;

FIG. 7 is a left, front perspective view of an electrical connector showing a second embodiment of my new design. The right, front perspective view is a mirror image thereto;

FIG. 8 is a front elevation view thereof;
FIG. 9 is a rear elevation view thereof;
FIG. 10 is a top view thereof;
FIG. 11 is a bottom view thereof;
FIG. 12 is a left side elevation view thereof. The right side elevation view is a mirror image thereto;
FIG. 13 is a left, front perspective view of an electrical connector showing a third embodiment of my new design. The right, front perspective view is a mirror image thereto;
FIG. 14 is a front elevation view thereof;
FIG. 15 is a rear elevation view thereof;
FIG. 16 is a top view thereof;
FIG. 17 is a bottom view thereof;
FIG. 18 is a left side elevation view thereof. The right side elevation view is a mirror image thereto;
FIG. 19 is a left, front perspective view of an electrical connector showing a fourth embodiment of my new design. The right, front perspective view is a mirror image thereto;
FIG. 20 is a front elevation view thereof;
FIG. 21 is a rear elevation view thereof;
FIG. 22 is a top view thereof;
FIG. 23 is a bottom view thereof; and,
FIG. 24 is a left side elevation view thereof. The right side elevation view is a mirror image thereto.
The dash-dot broken line portion of the figure drawings is included for the purpose of illustrating environment and forms no part of this ornamental design.

It is certified that error appears in the above-identified patent and that said Letters Patent is hereby corrected as shown below:

The title page showing the illustrative figure should be deleted to be replaced with the attached title page.

The DESCRIPTION on page 2, col. 1, under item (57), should be replaced with the following:

-- FIG. 1 is a left front perspective view of an electrical connector showing my new design. The right, front perspective view is a mirror image thereto;
FIG. 2 is a front elevation view thereof;
FIG. 3 is a rear elevation view thereof;
FIG. 4 is a top view thereof;
FIG. 5 is a bottom view thereof; and
FIG. 6 is a left side elevation view thereof. The right side elevation view is a mirror image thereto.
The dash-dot broken line portion of the figure drawings is included for the purpose of illustrating environment and forms no part of this ornamental design. --

Page 2, col. 2, line 28, should read, -- 1 Claim, 1 Drawing Sheet --

In the Drawings,

Fig. 1 should be deleted and Fig. 1 should appear as shown below:

FIG. 1
